INVENTOR
CLARENCE W. BENNETT

BY ATTORNEY

UNITED STATES PATENT OFFICE.

CLARENCE W. BENNETT, OF NEW YORK, N. Y.

VELOCIPED.

1,422,172.

Specification of Letters Patent. Patented July 11, 1922.

Application filed January 30, 1920. Serial No. 355,082.

To all whom it may concern:

Be it known that I, CLARENCE W. BENNETT, a citizen of the United States, residing at New York city, county of Bronx, State of New York, have invented certain new and useful Improvements in Velocipedes, of which the following is a specification.

The present invention relates particularly to the steering head and front fork construction of velocipedes, the objects of the invention being to improve and simplify these parts and at the same time to reduce the cost of the same without sacrificing either strength or durability.

These objects I have accomplished by a number of novel features of construction, combinations and arrangements of parts, the details of which will appear in the course of the following specification.

In the drawing accompanying and forming a part of the specification, I have illustrated the invention embodied in two different forms, but would have it understood that other variations and modifications may be made without departure from the scope of protection afforded by the appended claims.

Figure 1 in the drawing referred to is a perspective view of a velocipede having the features of the invention incorporated therein.

Figure 2 is an enlarged, broken and partly sectional view of the front fork and steering head construction.

Figure 3 is a plan view of the same as taken on substantially the plane of the section line 3-3 of Figure 2.

Figure 4 is a broken sectional view of a slightly different form of construction.

The frame of the machine illustrated comprises the two rearwardly and downwardly extending side pieces 5 and 6 supporting the seat 7. At the rear these side pieces of the frame are connected with the rear axle 8 and at their forward ends these side pieces are connected with a sleeve member 9 forming a head in which the tubular steering post 10 is journaled. This sleeve I have shown as made up of a piece of sheet metal folded upon itself to produce the tubular sleeve portion 9 and having its ends brought together into flat engagement, as indicated at 11 in Figure 3 and there secured between the side pieces as by means of rivets or other suitable fastenings 12.

In the first form of the invention disclosed, I have shown the lower end portion of the tubular steering post 10 as screw-threaded at 13 and have shown the fork construction as made up of the two side members 14 and 15 extended up through the two head plates 16 and 17 which are secured in spaced relation on the lower threaded end of the steering post between the nuts 18 and 19 and are held in the proper spaced relation by the interposed bushing or spacing tube 20.

To brace the sides of the fork below the head, I have provided a bracket or reinforcement of substantially U-form, inverted within the fork and having its base portion 21 engaged with the lower head plate 16 and its side arms 22 and 23 extending down along the side members 14 and 15 of the fork and secured thereto as by means of the rivets 75 or other suitable fastenings 24.

25 designates the handle bars which may be of any suitable or desired construction and which are shown as provided with a post or extension 26 adjustably secured within the 80 tubular member 10 of the steering post by a set screw 27 which is threaded in a collar 28 and extends through an opening in the tubular member 10 into engagement with the rod 26. The extension of this screw through 85 the opening in the tubular post 10 secures the collar 28 on the tubular post so as to cause said collar to act as a stop to prevent the post being accidentally withdrawn from the sleeve or head 9. On the removal of the 90 screw, the stop collar may be slipped off the post 10 and then the steering fork may be entirely withdrawn from the head 9, this, of course, after the handle bars have been removed.

95 The construction illustrated in Figure 4 differs from the form just described, principally in that the tubular steering post 10 is not threaded and the lower abutment 19^a which corresponds in a sense to the nut 19 100 in the first form is secured by riveting or turning over the lower end of the post, as indicated at 29. Also in this construction the spacing sleeve 20 is secured fast between the two head plates 16 and 17 by a rod 30 105 passed through the upper extended end portions of the sides 14 and 15 of the fork and through the bushing and the post. This rod may be secured in place by riveting the ends thereof over the fork sides, as indicated at 110 31. The upper abutment which I have designated 18^a corresponds in a general way

- to the upper nut 18 in the first form described, being disposed above the upper head plate 17 and forming a bearing engaging with the under side of the sleeve member 9.
- 5 This construction is like the one first described in that the handle bars may be readily raised and lowered and may be secured in any desired relation.

10 The invention, it will be evident, provides a relatively simple and light fork construction which is well braced and which can be readily assembled.

What I claim is:

1. In a velocipede, a frame and a tubular steering head carried thereby, a steering post journaled in said head, head plates secured in spaced relation on said post at a point below the steering head, a fork having side members extending up through said head plates, and a substantially U-shaped bracket inverted within said fork and having a base

portion secured in engagement with the lower head plate and downwardly extending side arms secured to the side members of the fork.

25

2. In a velocipede, a steering post, head plates on said steering post, a spacing sleeve on the post between said plates, abutments on the post above the upper head plate and below the lower head plate, fork members engaged with the head plates, and a substantially U-shaped bracket inverted between the fork members having a base portion secured by the lower abutment against the lower head plate and having dependent side arms secured to the fork members.

In testimony whereof I have affixed my signature in presence of two witnesses.

CLARENCE W. BENNETT.

Witnesses:

FRED. A. HAMEL,
FRANK GERICK.
